UNITED STATES PATENT OFFICE.

ROBERT DEHRENBACH, OF JERSEY CITY, NEW JERSEY.

NON-REFILLABLE BOTTLE.

980,925.

Specification of Letters Patent. Patented Jan. 10, 1911.

Application filed May 21, 1909. Serial No. 497,442.

To all whom it may concern:

Be it known that I, ROBERT DEHRENBACH, citizen of the United States, residing at Jersey City, in the county of Hudson and

5 State of New Jersey, have invented certain new and useful Improvements in Non-Refillable Bottles, of which the following is a specification.

This invention relates to non-refillable 10 bottles and has for its object to provide a comparatively simple and inexpensive device of this character, the construction of which is such as to effectually prevent an unauthorized person from fraudulently refilling the same with an inferior grade of 15 goods to replace that originally contained in the bottle.

A further object of the invention is to provide a bottle having main and auxiliary 20 valves, one of which is movable to open position by the weight of the liquid in the bottle when the latter is inverted thereby to permit the discharge of the contents of said bottle.

25 A further object is to so arrange the auxiliary valve with respect to the main valve that when the latter is opened and an attempt is made to refill the bottle, said auxiliary valve will be forced to its seat and thus 30 prevent the entrance of liquid to the interior of the bottle.

A still further object of the invention is generally to improve this class of devices, so as to increase their utility, durability and 35 efficiency, as well as to reduce the cost of manufacture.

Further objects and advantages will appear in the following description, it being understood that various changes in form, 40 combinations of the parts and minor details of construction may be resorted to within the scope of the appended claims.

For a full understanding of the invention and the merits thereof, and to acquire a 45 knowledge of the details of construction, and the means for effecting the result, reference is to be had to the following description and accompanying drawings, in which;

Figure 1 is a vertical sectional view of a 50 non-refillable bottle constructed in accordance with my invention; Fig. 2 is a similar view showing the bottle inverted to permit the discharge of the contents thereof; Fig. 3 is a transverse sectional view taken on the line 3—3 of Fig. 1; and Fig. 4 is a similar 55 view taken on the line 4—4 of Fig. 1.

Corresponding and like parts are referred to in the following description and indicated in all the views of the accompanying drawings by the same reference characters. 60

The device comprises a bottle or similar containing vessel 5, the neck 6 of which is reduced to form a contracted portion 7, the exterior walls of the neck above the contracted portion 7 being off-set to form transversely alined sockets 8.

Disposed within the neck 6 of the bottle is a casing 9 formed of porcelain, metal, wood or other suitable material and having its upper portion provided with a flat bearing surface 10 and its lower portion inclined to conform to and adapted to bear against the interior walls of the neck at the contracted portion 7 thereof.

Formed in the body of the plug or casing 75 9 are intersecting chambers 11 and 12 one of which opens through the flat bearing surface 10 of the casing 9 and constitutes a discharge passage for the liquid in the bottle. The lower end of the chamber 80 12 communicates with the interior of the bottle and is provided with a valve seat 13, there being a similar valve seat 14 formed in the chamber 11 at its point of connection with the chamber 12. 85

Slidably mounted in the chamber 12 is a valve 15 which serves to normally cut off communication between the interior of the bottle and the chambers 11 and 12, said valve being yieldably retained in its seat 90 by means of a coiled spring 16 interposed between the valve 15 and the adjacent end of the chamber 12 as shown. As a means for limiting the opening movement of the valve 15 there is provided a pin or lug 17 95 formed integrally with or secured to one of the end walls of the chamber 12 and arranged in the path of movement of the valve 15, the length of the pin 17 being such as to prevent further longitudinal movement of 100 the valve after the latter has cleared the opening 18.

Disposed within the chamber 11 and normally engaging the seat 14 is a ball valve 19 preferably formed of cork or other light 105 material, there being a depression 20 formed in one wall of the chamber 11 and adapted to receive the valve 19 when the bottle is inverted in the act of discharging the contents thereof. A pin 21 is extended transversely across the mouth of the passage or chamber 11 for the purpose of preventing 110

the escape of the ball valve during the discharge of the liquid in the bottle.

As a means for locking the plug or casing 9 within the neck of the bottle there are provided suitable springs 22, preferably secured to the opposite sides of the plug 9 and having their free ends bent laterally to form spring catches 23 adapted to enter the sockets 8 in the neck of the bottle, there being kerfs or recesses 24 formed in the adjacent walls of the plug or casing 9 for the reception of the free ends of the catches 23 when the plug or casing is positioned within the neck of the bottle. Thus it will be seen that by pressing the free ends of the catches 23 within the kerfs or recesses 24 the plug or casing 9 may be adjusted longitudinally within the neck of the bottle until said catches register with the sockets 8, when the catches will automatically enter the sockets 8 and thus lock the casing in position within the neck.

The lower end of the plug or casing 9 is cut away to produce a recess 25 one wall of which is curved laterally in the direction of the valve seat 13, thereby positively to direct the liquid in the body of the bottle through the valve seat when said bottle is inverted in the act of discharging said liquid. Attention is here called to the fact that the tension of the spring 16 is such as to permit the valve 15 to be moved to open position by the weight of the liquid in the bottle when the latter is inverted but to hold the valve firmly to its seat regardless of the position of the bottle when the latter is empty.

In order to discharge the contents of the bottle it is merely necessary to invert the same in the usual manner when the weight of the liquid will open the valve 15 and permit said liquid to pass through the valve seat 13 and opening 18, the liquid in its passage through the chamber 11 forcing the valve 19 within the depression 20 so as to permit the discharge of the liquid through the mouth of said chamber, and into a glass or other receptacle designed to receive the same. When the bottle is again placed in normal position the valve 19 will drop by gravity into engagement with the seat 14 while the spring 16 will automatically seat the valve 15 as will be readily understood. If an attempt is made to fraudulently refill the bottle while the latter is still partially filled with liquid, the valve 19 being made of cork will float to its seat so that the introduction of liquid through the mouth of the chamber 11 will only tend to more firmly retain the valve in engagement with said seat and thus effectually prevent the entrance of liquid to the interior of the bottle.

By arranging the valves 15 and 19 in the manner shown the auxiliary valve 19

forms a closure for the valve 15 so as to prevent an unauthorized person from surreptitiously introducing a wire or other instrument through the chamber or passage 11 with a view to lifting the valve 15 from its seat in order to force liquid within the body of the bottle.

If desired a cork or stopper 26 may be inserted in the neck of the bottle during transportation or storage.

While the mechanism forming the subject matter of the present invention is shown applied to a bottle it is obvious that the same may be used with equally good results in connection with jugs, jars and other liquid containing vessels without departing from the spirit of the invention.

Having thus described the invention, what is claimed as new is;

1. A bottle having a neck, a casing seated within the neck and provided with communicating passages, one of which opens through the top of the casing and the other through the bottom thereof, a float valve seated in one of said passages for normally closing the same, and a spring actuated valve entirely housed within the other passage and disposed at its point of junction with the first mentioned passage, said spring valve being movable to open position by contact with the liquid when the bottle is inverted and automatically to closed position when the bottle is in upright position, the float valve being disposed on one side of and forming a guard for the spring valve.

2. A bottle having a neck, a casing seated in the neck and provided with communicating vertical passages, one of which opens through the top of the casing and the other through the bottom thereof, a float valve disposed within one of said passages at the lower end thereof for normally closing the same, and a vertically disposed spring actuated valve entirely housed within the other passage at its junction with the first mentioned passage, said spring valve being normally extended across the lower end of the first mentioned passage at the seat of the float valve.

3. A bottle having a neck provided with oppositely disposed seating grooves, a casing disposed within the neck and provided with communicating vertical passages, one of which opens through the top of the casing and the other through the bottom thereof, a float valve disposed within one of the passages for normally closing the lower end thereof, a vertically disposed spring actuated valve entirely housed within the other passage at its point of junction with the first mentioned passage and extending across the lower end of said first passage at the seat of the float valve, there being a depression formed in the walls of the first mentioned passage near the upper end thereof for the

- reception of the float valve when the bottle is in inverted position, and locking members carried by the casing and engaging the seating grooves in the neck of the bottle.
- 5 4. A bottle including a neck having its lower end contracted and its intermediate portion provided with seating grooves, a casing disposed within the neck and having its lower end inclined to conform to and adapt-
10 ed to bear against the inclined walls of the contracted portion of the neck, said casing being provided with communicating passages, one of which opens through the top of the casing and the other through the bot-
15 tom thereof, a float valve disposed within one of the passages at the lower end thereof for normally closing said passage, and a spring actuated valve entirely housed within
- the other passage at its point of junction with the first mentioned passage and extending across the lower end of said first mentioned passage at the seat of the float valve, the wall of the passage opening through the bottom of the casing being inclined in the direction of the contracted portion of the neck, there being a depression formed in the wall of the other passage near the upper end thereof for the reception of the float valve when the bottle is inverted.
- In testimony whereof I affix my signature 30 in presence of two witnesses.
